UNITED STATES PATENT OFFICE.

CHARLES E. THOMAS AND JOHN F. WORRALL, OF WOONSOCKET, R. I.

YARN-SEPARATOR FOR SPINNING-MACHINES.

SPECIFICATION forming part of Letters Patent No. 256,174, dated April 11, 1882.

Application filed November 23, 1881. (No model.)

To all whom it may concern:

Be it known that we, CHARLES E. THOMAS and JOHN F. WORRALL, of Woonsocket, county of Providence, State of Rhode Island, have 5 invented an Improvement in Yarn-Separators for Spinning-Machines, of which the following description, in connection with the accompanying drawings, is a specification.

Our invention relates to spinning-machines; 10 and it consists essentially in operating the separators independently of the ring-rail.

As heretofore constructed the separators have been mounted upon a rock-shaft located near the ring-rail, and the separators, by a 15 suitable stop, have been held in horizontal position between the spindles when the ring-rail was in its lowest position; but when the ring-rail was lifted it acted upon and lifted the separators and turned the said rock-shaft. 20 The strain on the ring-rail when lifting a series of separators increases the wear of the guides for the ring rail, and ultimately renders its movements untrue. To obviate this wear of the guides we have devised mechanism independent of the ring-rail to automatically operate the rock-shaft carrying the separators, the mechanism herein shown for such purpose being partially the same as that employed to lift the ring-rail, so that the said separators are 25 operated simultaneously with the ring-rail, but are not actuated directly by it, as heretofore. The said independent mechanism is also so constructed that the separators may be lifted by the operator independently of the movement 30 of the rail and its lifting mechanism.

Figure 1 represents, in front elevation, a sufficient portion of a ring-spinning frame to illustrate our invention, the ring-rail being shown down in full lines, but elevated in dotted lines; 40 Fig. 2, a partial right-hand end view of Fig. 1, the shaft a^3 and some of the frame-work being broken out; and Fig. 3 is a sectional detail of the rods or shaft and separators and its backwardly-extended arms.

The ring-rail a , its lifting-rods a' , the arms a^2 a^{20} , on which they rest and by which the ring-rail is raised and lowered, the rock-shafts a^3 a^{30} and their arms a^4 a^{40} , and connecting-link a^5 , to operate the said rock-shafts together in 45 unison, are as common to ring-spinning frames 50

for lifting the ring-rail, and will be operated by the heart or other usual cam.

The separators b are extended centrally between the adjacent spindles s , and are adjustably attached by suitable screws to the parallel rods $c c$, having their end pieces, d , pivoted, as at e , (see Fig. 1,) so as to turn in the depending brackets e' . 55

At one end the pivoted separator-carrying rods $c c$, forming a sort of shaft, are provided 60 with an adjustable counter-weight, f , of sufficient size to nearly counterbalance the weight of the series of separators.

At the rear side of the rods $c c$, or shaft which holds the separators, we have attached 65 an arm, g , having preferably a curved face, as shown in Fig. 3. This arm g has a pin, g' , with which is connected one end of a suitable chain or cord, h , the other end of which is joined with a flanged hub, l , secured to a sleeve, l' , 70 having a finger, 3. The sleeve l' is placed loosely upon the shaft a^3 , but the finger 3 is made to rest against the finger 4 on the hub 5, which is adjustably secured to the said shaft a^3 . The weight of the separators is sufficient when they are horizontal, or until they 75 nearly reach a vertical position, to keep the finger 3 pressed against the finger 4, and as the shaft a^3 is rocked to raise and lower the ring-rail the finger 4 of the collar, acting 80 against the finger 3 of the sleeve l' , turns the hub l , and so draws upon the chain or connection h as to turn the rods $c c$ or shaft holding the separators, raising them gradually in advance of the rising ring-rail and permitting 85 them to follow down closely after the descending ring-rail, as will be understood.

If it is desired to lift the separators while the ring-rail is at rest, the sleeve may be turned on the shaft a^3 independently until the separators are brought into vertical position, as 90 shown in dotted lines, Figs. 1 and 2, when the weight f will maintain them in such position until again turned down for operation.

We claim—

1. The series of spindles, the separators b , extended centrally between adjacent spindles, the rocker-shaft with which the separators are attached, bearings to hold the rocker-shaft, and the connection h , combined with the hub 95 100

l, and with means to rotate the same to wind and unwind the connection *h*, turn the rocker-shaft, and raise and lower the separators, substantially as described.

5 2. The rock-shaft, its collar and finger, the loose sleeve *l*, its finger *3*, and hub *l*, and chain or connection *h*, combined with the separators, their holding rods or shaft, and the arm projecting therefrom, to which the said chain is joined, substantially as described.

In testimony whereof we have signed our names to this specification in the presence of two subscribing witnesses.

CHARLES E. THOMAS.
JOHN F. WORRALL.
